UNITED STATES PATENT OFFICE

ALFRED OBERLE, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR CONVERTING HYDROCARBONS

Application filed July 2, 1928, Serial No. 648,917. Renewed April 6, 1927.

This invention relates to improvements in a process and apparatus for converting hydrocarbons and refers more particularly to the destructive distillation of hydrocarbon products to extract therefrom the lower boiling point oils having the characteristics of gasoline and the like.

Among the objects of the invention are to provide a process in which the oil is primarily treated in a heating zone, thence passed to a vaporizing chamber, the evolved vapors passing off to be dephlegmated and condensed while the carbons laden products are drawn off and treated in a coking still; to provide a process in which a separation is made between the carbon laden oil and the relatively carbon free oil removed from the vaporizing chamber, whereby one portion may be treated in a coking still, while the other is recycled and retreated for the lighter fractions remaining in the oil.

Fig. 1 is a diagrammatic end view of the apparatus with parts broken away and parts in section. Fig. 2 is an enlarged end view of the conversion tower, heating coils and coking still. Fig. 3 is a view taken along line 3-3 in Fig. 2. Fig. 4 is an enlarged view of the valve arrangement between the conversion tower and coking still. Fig. 5 is a view taken along the line 5-5 in Fig. 4, and Fig. 6 is a detail view of the plate between the tower and coking still through which the residual substances pass.

Referring to the drawings, 1 is a heating coil mounted in a furnace 2 connected by a transfer line 3 to the conversion tower 4. The upper portion of the conversion tower designated as 4-a, consists of a fractionating arrangement hereinafter explained in detail. The lower portion designated as 4-b comprises an expansion tank in which a liquid level is maintained. Below the conversion tower is the coking still 5 in which the residual substances are treated. The fractionating tower is connected by vapor line 6 to a water condenser 7, the latter being connected by a line 8 to the receiving tank 9. At 10 is shown an absorption tank into which the raw oil is introduced and through which the uncon- densable gas passes.

Describing now the method of operating the process, the oil to be treated is introduced from any convenient extraneous source through the line 11, and is permitted to rise in the absorption tank overflowing through 55 the pipe 12 into the line 13 communicating with the suction side of the pump 14. This pump forces the oil through the line 15 in order that it may be supplied either into the top of the dephlegmator through the line 60 15-a controlled by a valve 16, or through the line 15-b into the pool of oil maintained in the conversion chamber. The line 15-b is controlled by a valve 17. If charged into the top of the fractionating tower, the charging stock is utilized as a refluxing medium, being introduced by the spray pipe 18 into the perforated pans 19 positioned in the open ended cylinder 20. This cylinder has a perforated bottom shown at 21, which supports 65 balls 22 of a catalytic material such as aluminum, nickel or other metallic substances. The lower skirt of the cylinder is flared as shown at 23, the bottom edge being immersed in a pool of oil maintained in a trough shown 70 at 24. If charged into the top of the fractionating tower, the charging stock will percolate down over the perforated pans through the catalytic balls and perforated bottom 21, thence dropping into the pool of oil maintained in the lower portion of the tower. If charged directly through the line 15-b, it 75 will be introduced to the pool without being utilized as a refluxing medium. The oil is drawn from the pool through the curved 80 drawoff pipe 25 which has interposed therein a carbon trap 26. The oil is thence passed to the pump 27 which discharges it through the line 28 regulated by a valve 29 into the heating coil 1. In the heating coil, the oil 85 is raised to a conversion temperature passing from the coil through the transfer line 3 and introduced into the pool of oil in the conversion tower at a point just below the fractionating portion of the tower. On being introduced to the conversion tower, the vapors evolved rise, passing up through the catalytic material and perforated pans, thence downwardly through the channel 30 90 formed by positioning the closed top recep- 100

tacle or container 31 over the inner cylinder, leaving a space between the outer wall of the inner open ended cylinder and the inner wall of the closed top receptacle 31. The vapors 5 passing downwardly through the channel 30 pass out from the open bottom and rise again through the channel 32 between the outer shell of the container and the wall of the tower. In this passage are positioned a plurality 10 of circular pans 33. The vapors then rise into the top of the tower and are withdrawn through the vapor line. Any reflux condensate collecting in the upper portion of the tower will flow over the top of the container 15 or receptacle 31 and drip down over the pans 33, finally collecting in the pool collected in the trough 24. The overflow from this trough drips back into the pool maintained in the conversion chamber. The vapors with- 20 drawn from the top of the tower pass off through the line 6 to the water condenser 7 and are collected in the distillate receiving tank 9 after passing through the pipe 8 connected with the discharge end of the con- 25 denser coil.

The receiving tank is equipped with a pressure gauge 34, a gas relief line 35 controlled by a valve 36 which communicates with the lower portion of the absorption receptacle 30 into which the charging stock is introduced. Thus the uncondensable gas is relieved of any lighter oil fractions contained therein by being passed through the body of raw oil charging stock contained in the absorption tank 35 10. Any excess gas may be drawn off from the top of the tank through the line 36—a controlled by a valve 37. A liquid overflow line is supplied for the tank at 38, controlled by valve 39. The distillate in the receiving 40 tank may be drawn off through the pipe 40 controlled by a valve 41, or returned for re-treatment in the system through the line 42 controlled by a valve 43, whereby it may be introduced to the charging line 13. Thus 45 under certain conditions, the distillate may be utilized as a refluxing medium either in combination with the raw oil or without the raw oil. In the latter instance, it would necessitate the closing of the valve 44 in the 50 line 12.

The oil body in the tower is kept in a turbulent condition and the carbon in suspension, by an agitator consisting of a vertical shaft 45 upon which are positioned vanes or 55 blades 46. In addition to keeping the oil in agitation, these vanes are so positioned that they serve as scrapers along the bottom and sides of the tower.

Below the conversion tower is positioned a 60 coking still 5. Between the tower and the still is a valve arrangement shown in detail in Figs. 4, 5 and 6. Between the lower flange of the tower and the upper flange of the inlet pipe to the coking still is placed a valve 65 plate 47. This valve plate is perforated as

shown at 48 by cut-out sectors or apertures with which the aperture 49 in the valve 50 registers in its rotation due to its being fixedly mounted upon the shaft 45. Thus as the valve 50 rotates in consecutive registration 70 of the port 49 with the ports 48, the residual hydrocarbon products from the bottom of the conversion tower are discharged into the coking still. Although a rotating valve of this type is shown, it is understood that any 75 suitable type of communication may be arranged between the tower and still in order that the oil in the conversion tower may be maintained under any suitable pressure, while the hydrocarbons undergoing treatment in the coking still are maintained under reduced pressure, or substantially atmospheric condition. Longitudinally of the coking still is mounted a shaft 51 which carries the agitating or scraper blades 52. These blades 80 are pitched in a manner that in addition to keeping the oil or coky substance in agitation, also cause a movement of the materials from one end of the still to the other, that is, from the end of the still into which they are introduced to the opposite end from which the treated material is discharged. The residual substances introduced to the coking still through the rotating valve arrangement explained, collect in the still and are kept in 85 constant agitation by the scrapers 52. While in this coking still, the hydrocarbon materials are subjected to the heat of the flue gases passing from the furnace 2 through the flue pipe 53 in which is positioned a damper 54, and thence through the heating compartment 55 arranged around the lower portion of the coking still, or that portion in which the liquid products are contained. It is inadvisable to circulate the hot gases about the entire still due to overheating of the materials being treated. Vaporous products evolved 90 in the coking still pass off through the vapor line 56 to a condenser 57 from which they may be withdrawn in liquid condition through line 58 controlled by valve 59. On the shaft 51 and shaft 45 respectively, are bevel gears 60 and 61 which serve to drive the vertical shaft 45 upon which the agitating scrapers 46 are positioned. The damper 54 100 in the flue 53 may be utilized to control the quantity of heated gases circulated about the coking still, and also in case of rupture of a tube in the furnace to prevent the oil from passing into the flue and cause excessive heat or burning out the coking still, 105 which would result in large conflagration. 110

The heavy viscous residual substances may be withdrawn from the coking still through the drawoff line 62 controlled by a valve 63. 125

During the initial stages of operation it may be advisable to recirculate certain of the hydrocarbon products discharged into the coking still, as the temperatures in the system may not have been such to effect proper 130

- conversion. For this purpose a line 64 is tapped into the bottom of the coking still with a communicating connection 65 to the suction side of the pump 27 whereby this oil 5 may be circulated to the heating tubes until it contains an objectionable quantity of free carbonaceous material. Valves 66 and 67 are interposed in the lines 64 and 65 respectively, for controlling this flow.
- 10 The process furnishes a means for treating oil continuously and utilizing the heat of the system not only to convert the oil into lower boiling point distillates, but also to treat residual material in a single operation.
- 15 The tower is so arranged that an effective and efficient control of the oil fractions may be obtained, thereby regulating within close limitations the character of the resultant distillate and recycling only those portions of 20 the unvaporized hydrocarbons which do not contain any excessive free carbon material. The tower is preferably surrounded by an insulated shell 68, the upper part or fractionating portion of the tower being separated by 25 an insulating ring 69 from the lower conversion portion. It will be understood that ventilating shutters may be provided in the upper portion of the insulating shell to give further control of the fractionating portion 30 of the tower.
- The system is preferably operated continuously and under pressures commensurate with the requirements of the oil undergoing treatment.
- 35 The coking still, as explained, is operated under substantially atmospheric conditions.
- By treating a fuel oil of substantially 15° Baume to temperatures ranging from 600° to 900° F., and pressures of substantially 125 40 pounds, a yield of from 30% to 45% of good quality low boiling point distillate may be obtained. The residual substances may be relieved of their volatile content by utilization 45 of the heat in the flue gases, producing overhead products containing lubricating stock, while a coky viscous substance was continuously removed from the coking still.
- I claim as my invention:
1. A process of converting hydrocarbons 50 consisting in introducing the charging oil to a pool in a conversion zone, withdrawing the oil from said pool and passing it through a heating zone and there raising it to a conversion temperature, directing the heated oil to the conversion pool, subjecting the vapors evolved to a refluxing and condensing action, passing the unvaporized products to a coking zone, distilling the unvaporized products under reduced pressure conditions in said zone 55 by the heat of the partially expended flue gases from the heating zone, and maintaining the hydrocarbon products in the conversion pool and coking zone in a turbulent condition to prevent deposition of the free carbon.
